UNITED STATES PATENT OFFICE.

GLENN H. SEELY, OF AKRON, OHIO.

SYSTEM FOR CONTROL OF BOILERS OR THE LIKE.

Application filed May 23, 1925. Serial No. 32,413.

This invention relates to a mechanism for the automatic control of steam boilers or other heating or power systems or furnaces, and is designed to secure a more even operation of the various units of the power plant so as to secure more regular and economical production. The invention comprises a plurality of interconnected and interdependent instrumentalities which are automatically 10 and accurately controlled.

In this application is shown one embodiment of the invention, it being understood, however, that changes and modifications may be resorted to within the scope of the invention.

In the drawings:

Figure 1 is a diagrammatic view of the complete installation as adapted for a single steam boiler unit;

Figure 2 is a side elevation of the control device; and

Figure 3 is a plan view thereof.

In the drawings, the boiler or furnace is indicated by the numeral 1, the main steam line being indicated by the numeral 2 and a mechanically operated stoker of any preferred type being indicated by the numeral 3. A pipe 4 is set in the wall of the boiler and opens at its inner end over the fire bed. This pipe 4 is brought outwardly from the fire box and is opened into a bell, the lower end of which is immersed in an oil bath 6 in a reservoir 7. The bell 5 is carried upon one end of a pivoted scale beam 8, the other end of which supports a second bell 9 dipping into the oil bath 10 in a reservoir 11, the two reservoirs being connected by a pipe 12. The bell 9 serves, therefore, as an equalizer or balance for the bell 5. Rocking of the beam 8 is limited by set screws 13. The bell 5 is subjected to the differences in pressure existing in the fire box above the fire, and when the pressure within the furnace above the fire is low, the bell 5 will be depressed, and when the pressure builds up in the fire box, the bell is raised, and the rocking of the scale beam 8 is utilized to control the various instrumentalities within the system.

The scale beam 8 is provided with an adjustable pin 15 which is located on the end of the arm carrying the bell 9 and this pin is situated beneath and adapted to operate a valve 16 which admits air from the pressure line 17 which is supplied with compressed air from any suitable source, through a sepa-

rator 18. When the pressure within the furnace is low the bell 5 is drawn downwardly, opening the valve 16 and admitting air under pressure from the line 17 to the line 19 by which it is conducted to the upper side 60 of a piston 20. The piston 20 is connected by a rod 21 with the damper 22 in the stack 23 so that the damper will close or open as the pressure decreases or increases, respectively.

At the same time that the damper is regulated in the manner described, it is advantageous to regulate the speed of the stoker so that more or less coal will be supplied to 70 the grate. This is accomplished by a chain 24 which is connected at one end to the rod 21 and at the other to a pivoted and weighted lever 25 which controls the governor 26 of the engine which operates the stoker 3, 75 the action being such that as the pressure decreases the stoker will be retarded and a thinner bed of coal will be laid upon the grate.

In actual practice the various elements balance so nicely that there is very little variation in the operation of the furnace.

In connection with the regulation of stack, damper and the stoker, the installation also makes provision for the regulation of the 85 fan and the damper in the draft passage from the fan to the grate. In the present installation this is accomplished from the header 27 on the steam line, by means of a small pipe 28 connected with a pressure regulating valve indicated at 28^a controlling flow of air from the supply line into two branch pipes 29 and 30. The former branch leads to a diaphragm valve which controls the passage of steam through the steam line 32 to the turbine 33 which operates the fan 34. The branch 30 leads to a diaphragm 35 which, through lever mechanism 36, operates the damper 37 located within the main air duct 38 from the fan to the furnace. In this manner the steam pressure in the header 27 controls the speed of the fan and the amount of air entering the fire box. The amount of air forced within the fire box by the fan also directly affects the pressure above the fire and in this manner the whole system is coordinated and regulated to obtain evenness of operation and efficiency.

The system of the invention is adapted for accurate control due to the incremental movement of the controlling air valves which have no inoperative movements and which

operate the various mechanisms directly without the intervention of levers, links, etc., which are subject to considerable lost motion. The control devices are adapted to be mounted remotely from the boiler. It is obvious that, having explained the invention so that it may be understood by those skilled in the art, changes and modifications may be made, which, however, will embody the features of the invention within the scope of the claims appended hereto.

What is claimed is:

1. In combination with a boiler, a mechanical stoker, an adjustable flue damper, a fan, a duct extending from the fan to the boiler, an adjustable air supply damper in said duct, means for controlling the speed of the stoker and for adjusting the flue damper, said means being operable by fluid pressure controlled by pressure of gases above the fire pot of the boiler, means for controlling the speed of the fan and means for adjusting the air supply damper, each of said last-named means being operable by fluid pressure controlled by delivery of steam from the boiler, each of said control means operating independently of the other, a fluid pressure supplying system, connections therefrom to the first control means, a valve in said connections operable by pressure of gases above the fire box, connections from the fluid pressure supply system to each of the second control means, and a single regulator for the supply of air pressure through both last-named connections, said regulator being operable by delivery of steam from the boiler.

2. In combination with a boiler, a mechanical stoker, an adjustable flue damper, a fan, a duct extending from the fan to the boiler, an adjustable air supply damper in said duct, means for controlling the speed of the stoker and for adjusting the flue damper, said means being operable by fluid pressure controlled by pressure of gases above the fire pot of the boiler, means for controlling the speed of the fan and means for adjusting the air supply damper, each of said last-named means being operable by

fluid pressure controlled by delivery of steam from the boiler, a fluid pressure supplying system, connections therefrom to the first control means, a valve in said connections operable by pressure of gases above the fire box, connections from the fluid pressure supply system to each of the second control means, and a single regulator for the supply of air pressure through both last-named connections, said regulator being operable by delivery of steam from the boiler.

3. In combination with a boiler, a mechanical stoker, an adjustable flue damper, a duct for delivering air to the boiler, an adjustable air supply damper in said duct, means for controlling the speed of the stoker and for adjusting the flue damper, said means being operable by fluid pressure controlled by pressure of gases above the fire pot of the boiler, means for adjusting the air supply damper, said last-named means being operable by fluid pressure controlled by delivery of steam from the boiler, a fluid pressure supplying system, connections therefrom to the first control means, a valve in said connections operable by pressure of gases above the fire box, connections from the fluid pressure supply system to the second control means, and a single regulator for the supply of air pressure through the last-named connections, said regulator being operable by delivery of steam from the boiler.

4. In combination with a boiler, a mechanical stoker, an adjustable flue damper, a fan, a duct extending from the fan to the boiler, an adjustable air supply damper in said duct, means for controlling the speed of the stoker and for adjusting the flue damper, said means being operable by pressure of gases above the fire pot of the boiler, means for controlling the speed of the fan, and means for adjusting the air supply damper, each of said last-named means being operable by delivery of steam from the boiler, each of said control means operating independently of the other.
